UNITED STATES PATENT OFFICE.

OLLYN A. LAYNE, OF LOS ANGELES, CALIFORNIA.

SEPARATOR FOR WELLS.

1,403,174.

Specification of Letters Patent. Patented Jan. 10, 1922.

Application filed July 24, 1918. Serial No. 246,572.

To all whom it may concern:

Be it known that I, OLLYN A. LAYNE, a citizen of the United States, residing at Los Angeles, in the county of Los Angeles, State of California, have invented new and useful improvements in Separators for Wells, of which the following is a specification.

This invention relates to separators adapted to separate fluids and solids and to prevent sand and the like from entering a well pipe or casing along with the water or oil or gas. It is a general object of this invention to provide a separator construction which is efficient in its operation and simple and inexpensive in construction, the primary object of the invention being the production of a separator so constructed as to be adapted to effectively resist, and remain in operative position against the pressures to which it is subjected in actual usage. This general object is attained by the devices hereinafter described. And there are also several other objects which will be best understood from a description of the device itself.

Heretofore well separators have been used in which an apertured pipe is provided with strainer or separator plugs or buttons. It is an object of this invention to provide a new form of strainer plug or button and to provide a new means of fastening such plugs or buttons in the pipe. The construction is such that it permits the use of a larger sized plug than has heretofore been possible, and consequently permits the use of larger openings and larger separating members in the plugs; and further permits the plug and separating members to conform in curvature to the contour of the pipe wall. Furthermore, the construction is such that the plug, and the separating members also, may be equal in thickness to the full wall thickness of the pipe. I have found that one of the most effective forms of separators is that embodying a horizontal slit or a horizontally extending opening—in contradistinction to a vertical slit or the like. Now, in order to use such a horizontal slit or the like, and to have the slit or other opening of sufficient size to pass fluid in quantity, it is necessary to make a button or plug of considerable diameter. My invention has to do particularly with a specific construction whereby the advantages of such a slit or opening are attained in a button or plug.

Further features of the invention are ease of manufacture; and, particularly, ease of preparation (if it becomes necessary) in the field. All of these objects and features, and others, will be best understood from the following detailed description of a preferred form of my invention, reference being had for the purpose of this description to the accompanying drawings in which a preferred form of device is illustrated, and in which—

Fig. 1 is an elevation illustrating a pipe equipped with my separating members and forming a separator in accordance with this invention; Fig. 2 is an enlarged exterior elevation showing a single plug; Fig. 3 is a section taken on line 3—3 of Fig. 2; Fig. 4 is a section taken on line 4—4 of Fig. 2; and Fig. 5 is a section similar to Fig. 4 showing the apertured pipe as it appears before insertion of the plug; Fig. 6 is a section similar to Fig. 3 showing a modified construction; and Fig. 7 is an elevation of the form shown in Fig. 6.

In the drawings the numeral 10 designates the wall of a well pipe. This pipe may be of any desired diameter and the wall of any suitable thickness. Wherever I wish to insert a separator plug 11, I form in the pipe wall 10 a circular opening or aperture 12 and then screw-thread that opening or aperture as shown at 13. The aperture and the screw threads are preferably tapered, tapering inwardly. This aperture and the threads thereof are preferably, in actual manufacture, made with a standard sized drill and a standard sized tap—such as, for instance, an inch and a quarter or an inch and a half pipe tap—so that if necessary or desirable a pipe may be prepared and the plugs 11 inserted in the field.

The plugs 11 are shaped to conform to the curvature of the pipe wall 10 and are provided with openings 14 through which fluid may flow into the pipe. For the purposes of the present invention these openings 14 may be of any desired character, and the separator member or members 15 between them may be of any desired character. I prefer, however, in one form of device, to use openings which extend inwardly and upwardly to the interior so as to prevent inward flow of sand by a process of separation rather than by a process of straining. However, it will be understood that in this

specification, and in the following claims, I mean the term separator to cover all kinds of separation, including straining, etc. In Figs. 6 and 7 I show openings 14^a in the form of slits wider at their back faces than at their front faces; the bars 14^b between the slits being wider at their outer faces than at their inner faces, the purpose of such construction being to insure that all matter which goes into the slots will find its way into the pipe, and not lodge in the slots and clog the same. In each form of opening it will be seen that the opening extends horizontally across the face of the plug which is of a contour or curvature corresponding to that of the casing wall. The plug is of the full wall thickness, giving to the openings a depth equal to the full wall thickness and thereby increasing to a maximum the efficiency of action of the openings which depends upon their depth. The finished separator pipe has a flush smooth surface, both inside and out.

The peripheral exterior of the plug is tapered and is screw threaded as illustrated at 16. The plug is preferably made by casting, the apertures 14 or 14^a, the screw-threads 16, and the curved inner and outer faces 17 and 18 being all formed at a single operation. The plug is also formed with one or more superficial indentations or peripheral notches as shown at 19 into which a portion of the metal of the pipe wall is upset as illustrated at 20. It is the function of these upset portions to prevent rotation of the plug, not to directly prevent inward and outward movement of the plug. The screw-threads prevent outward and inward movement of the plug except by rotation; and the upsets at 20 prevent that rotation. The plug is made of a certain predetermined standard size; and when the pipe aperture is screw threaded to that certain pre-determined standard size (which it may be by using a standard tapered tap and working the tap to a standard depth), then the plug will screw into the tapered threaded opening to a certain position and will then screw tightly into its proper position in which its inner and outer surfaces are flush with the outer and inner surfaces of the pipe wall and conform to those surfaces. The taper of the screw threads may be such that the plug will be tight and at the same time may be turned up to proper position (with its openings in proper position). With a small amount of taper and with the threads fitting nicely, the plug will always be tight when adjusted to proper position. There is, due to this tight screw-threaded engagement, very little tendency of the plug to rotate. Consequently, there is very little strain upon the upsets 20.

It is one of the excellencies of this device that the plugs and their separating or

straining openings may be made of larger size than has heretofore been the case and that the openings may extend horizontally some considerable distance. Heretofore plugs have been placed in shouldered openings in the pipe wall. In order to provide an opening with a shoulder all around, the size of the plug is necessarily limited—that is, the plug cannot extend very far around the circumference of the pipe. With screw threads it is immaterial how far the plug extends in a circumferential direction around the pipe. No one thread has to be or form an annular shoulder entirely around the plug, as is necessary where a shouldered opening is used. Consequently, I am enabled to use a larger plug, make the plug conform in curvature and thickness to the curvature and thickness of the pipe, and use larger separating or strainer openings than can otherwise be used; and I can make those openings horizontal. The use of larger plugs and larger openings gives greater straining and separating capacity and very much reduces the cost of making the separator.

It is obvious that the formation of the slots 14^a, enclosed at the sides by the bars 14^b, which latter have outer peripheries conforming to the contour of the outer surface of the pipe 10, produces, in said bars, a construction which is outwardly-arched with respect to the longitudinal axis of the pipe. It is a fact that an arched-span between two fixed points offers the greatest resistance against pressure directed inwardly between said points. In my construction the outer periphery 16 of the plug is seated against the inner wall 13 of the opening 12 in the pipe. In actual usage great external pressure is concentrated upon the strainer plugs and this pressure is directed throughout the entire length of the bars 14^b, at the side of the slots 14^a. But said bars 14^b, being of outwardly-arched formation, transmit the pressure to the screw-threaded wall 13 of the pipe-aperture 12, and the bars 14^b are neither bent nor distorted. It is obvious that, before the bars could be bent inwardly, they must first be twisted laterally. It will also be noted that the bars 14^b present an outer surface which is of a width materially less than the thickness of said bars, whereby the pressure receiving portion of the bars is narrower than the portion which resists it. It will be seen therefore, that the bar cannot be bent inwardly, because it cannot even be straightened inwardly.

It is of great advantage to have the plug in screw-threaded engagement with the wall surrounding the pipe-aperture, throughout the width of the plug and said wall. Each of the screw-threads upon the wall co-operates with an engaged thread on the plug, to prevent lateral movement of the plug in

either direction; consequently the more threads that are provided, the more the resistance offered to such movement. In certain instances in actual use, it is necessary 5 to apply outward pressure from within the pipe, and it will be noted that the co-operating threads prevent the plugs being blown outwardly under such circumstances.

Various modifications of a plug provided 10 with outwardly-arched portions, will be suggested to those skilled in the art, but my invention comprehends all such embodiments as fall within the scope of the appended claims.

15 Having described a preferred form of my invention, I claim:

1. A well separator comprising, in combination, a pipe having an aperture therein, and a plug in said aperture and of substantially the same thickness as the pipe wall, the 20 said plug being slotted therethrough, the portions of the plug enclosing said slot constituting outwardly-arched, bar-like members.

25 2. A well separator comprising, in combination, a pipe having an aperture therein, a plug seated in said aperture and provided with elongated openings, the portions of the plug enclosing said openings constituting 30 outwardly-arched bar-like members and means on the plug, cooperating with means carried by the pipe, for holding said plug against lateral movement in either direction, with respect to said pipe.

35 3. A separator for well pipes comprising a slotted plug having a main body portion adapted to conform to the contour of the outer surface of the pipe to which it is fitted, portions of said plug being outwardly-arched with respect to the longitudinal axis 40 of the pipe, and constituting separated bar-like members adapted to transmit to the pipe wall and substantially circumferentially thereof, inward pressure applied to said 45 portions.

4. As a new article of manufacture, a separator plug for well pipes, shaped to conform to the outer surface of the pipe, and provided with elongated slot-like openings, the 50 portions of the pipe coming between openings constituting outwardly-arched, bar-like members, substantially as described.

5. A well separator comprising, in combination, a pipe having an opening therein, a 55 plug fitted into said opening and provided with a slot or slots affording communication between the outside and inside of said pipe, and outwardly-arched members enclosing said slot or slots on each side, said members being adapted to bear against the edge of the wall enclosing the opening in the pipe, when external pressure is applied to the 60 members, substantially as described.

6. A well separator comprising in combination, a pipe having an aperture therein

and a plug in said aperture, said plug being of substantially the same thickness as the pipe wall and having a curved outside surface conforming to the outside surface of the pipe wall, and elongated slots through 70 the plug which extend substantially in the direction of curvature and circumferentially of the pipe, the portions of the plug coming between slots constituting outwardly-arched, 75 bar-like members.

7. A well separator comprising in combination, a pipe having an inwardly tapering aperture therein and a correspondingly tapered plug in said aperture said plug being of substantially the same thickness as 80 the pipe wall and having a curved outside surface conforming to the outside surface of the pipe wall, and elongated slots through the plug which extend substantially in the direction of curvature and circumferentially 85 of the pipe, the portions of the plug coming between slots constituting outwardly-arched bar-like members.

8. A well separator comprising in combination, a pipe having an aperture therein 90 and a plug in said aperture, said plug having a curved outside surface which conforms substantially to the curvature of the pipe wall, and elongated slots through the plug 95 which extend in the direction of curvature and circumferentially of the pipe, the portions of the plug coming between slots constituting outwardly-arched bar-like members.

9. As a new article of manufacture, a separator plug for well pipes of substantially 100 the same thickness as the wall of the pipe and curved to conform to the outside curvature of the pipe and provided with elongated, slot-like openings extending substantially 105 in the direction of curvature, the portions of the plug coming between slots constituting outwardly-arched bar-like members.

10. As a new article of manufacture, a separator plug for well pipes of substantially 110 the thickness of the wall of the pipe, said plug being provided with elongated, slot-like openings extending substantially in the direction of the pipe curvature, the portions of the plug coming between slots 115 constituting outwardly-arched bar-like members.

11. A well separator comprising, in combination, a pipe having an aperture therein, a plug seated in said aperture, and elongated openings extending through the plug, the portions of the plug enclosing said openings being outwardly-arched and of greater thickness than width, substantially as described, and for the purpose set forth. 120

In witness that I claim the foregoing I have hereunto subscribed my name this 13th day of July, 1918. 125

OLLYN A. LAYNE.
